(57) **CLAIM**

The ornamental design for an acoustic earplug as shown and described.

DESCRIPTION

FIG. 1 is a front, right and top perspective view of an acoustic earplug, showing my design.
FIG. 2 is a rear, left and bottom perspective view thereof.
FIG. 3 is a rear, right and top perspective view thereof.
FIG. 4 is a front elevation view thereof.
FIG. 5 is a rear elevation view thereof.
FIG. 6 is a left side elevation view thereof.
FIG. 7 is a right side elevation view thereof.
FIG. 8 is a top plan view thereof; and,
FIG. 9 is a bottom plan view thereof.
The dashed broken lines depict portions of the acoustic earplug that form no part of the claimed design.
